UNITED STATES PATENT OFFICE.

LAWRENCE C. NELSON, OF DETROIT, MICHIGAN, ASSIGNOR TO STEWART MANUFACTURING CORPORATION, OF CHICAGO, ILLINOIS, A CORPORATION OF DELAWARE.

CARRIAGE CURTAIN WINDOW.

Application filed May 23, 1921. Serial No. 471,844.

To all whom it may concern:

Be it known that I, LAWRENCE C. NELSON, a citizen of the United States, and a resident of the city of Detroit, in the county of Wayne and the State of Michigan, have invented certain new and useful Improvements in Carriage Curtain Windows, of which the following is a specification, reference being had to the accompanying drawings, forming a part thereof.

The purpose of this invention is to provide an improved automobile curtain window frame construction more securely water-tight and more easily and quickly assembled than those heretofore used. It consists of the elements and features of construction shown and described, as indicated in the claims.

In the drawings:

20 Figure 1 is a fragmentary outside view of an automobile equipped with a window embodying this invention.

Figure 2 is a transverse sectional view of the frame part on an enlarged scale, 25 showing also fragmental portions of the curtain and window glass in position preparatory to assembling or clamping the frame to the curtain.

Figure 3 is a view similar to Figure 2, 30 except that the parts are shown in completely assembled and clamped position, the section being made at the position of one of the securing or clamping screws.

Figure 4 is a section similar to Figure 3, 35 but made at the transverse plane of extent of curtain stay straps which are provided for relieving the curtain of the weight of the window, as at the line, 4—4, on Figure 1.

40 Figures 5 and 6 are inner side plan views of opposed and mated portions of the two frame members between which the glass and the curtain are engaged.

Figure 7 is a section at the line, 7—7, 45 on Figure 4.

As shown in Figure 1, the curtain of the usual fabric or leather is indicated at 1, and a glass window, 2, is shown mounted therein by means of a two-part frame composed of 50 mated parts, 3 and 4, which are of similar outline, but adapted to be secured against opposite faces respectively of the curtain which, as well as the glass, is thereby seated between them. The parts, 3 and 4, as shown 55 in certain of the figures, are held together

by means of screws, 5, and these screws, it may be understood, are disposed at fairly frequent intervals around the frame; but certain of them are employed at special positions as hereinafter particularly pointed out.

For manufacturing convenience, the frame parts, 3 and 4, are preferably die cast, and in some instances are very slightly warped in cooling. It is also found in practice that the glass 2, unless selected with extreme care, varies somewhat in thickness. As a result of this irregularity or the warping above indicated, or from both causes, it becomes difficult to clamp the glass 2 securely between the frame members, 3 and 4, without imposing uneven pressure upon it, which is liable to result in breakage, either during the assembly or shortly after the installation of the glass in the curtain.

To overcome this difficulty the frame member, 3, is formed with a continuous groove or channel, 7, extending along the inner marginal portion, and a yielding gasket or cushion strip, 8, preferably of rubber, is lodged in this groove with a considerable portion of its cross-section extending above the plane of the edge of the groove to afford lodgment for the glass, 2. The yielding nature of the cushion strip 8, permits drawing down the connecting screws, 5, so that the frame parts, 3 and 4, are firmly clamped together while the glass itself is subject to a yielding and substantially uniform pressure between the frame members and in addition the gasket prevents the entrance of moisture past the edge of the glass. Perfect seating of the gasket not only on the glass but also on the walls of the groove, 7, is important. Complete and uninterrupted seating is best obtained when the initial contact of the gasket with the seating surface is a mere line, but the seating must be extended over an area of some width in order to insure effective exclusion of moisture. It is also desirable and considerably important that in the completely assembled and clamped together position of the parts the gasket should completely occupy the groove, 7, that is, should leave no unclosed or unoccupied space at the bottom of the groove under the gasket. All these purposes are accomplished by the construction shown in which the groove, 7, has flaring sides and a curved bottom, making it in general or approximately

parabolic in cross-section, and the gasket is normally, that is, before compression,—curvilinear in cross-sectional outline; and the most conveniently or easily producible form meeting this requirement is cylindrical,—that is, circular in cross-section as shown. It will be seen that with this form of groove and gasket, the initial contact of the gasket with the two sides of the groove 10 is at lines of tangency to the curvilinear cross-sectional outline of the gasket, and that the contact of the gasket with the glass is at the line of tangency with the cross-sectional curvilinear outline with the plane 15 of the glass, all said contacts, therefore, being theoretically at a mere line. And it will be seen that when the gasket is compressed in forcing and securing the two members of the frame together, as seen in Figure 3, 20 the lines of contact of the gasket with the groove sides are extended into considerably wide areas, and that by reason of the curvilinear form of the bottom of the groove, and the elastic compressibility of the gasket, the 25 latter will be forced into complete contact with the groove throughout the curved portion at the angle between the two flaring or diverging sides, thus making a completely continuous area of contact of the gasket with 30 the groove, and occupying the groove to the bottom thereof; and as to the contact of the gasket with the plane of the glass, it will be seen that the original line of initial contact is expanded into an area of appreciable 35 width, the gasket probably being forced out into the crevice between the edge of the glass and the shoulder, 4^a, of the rabbet in the frame member 4 in which the glass is seated and into which the engaged marginal portion 40 of the curtain fabric extends.

As above noted, the frame member, 4, has a rabbet for receiving the glass whose shoulder 4^a transverse to the plane of the opposed curtain-engaging faces of the 45 frame, co-operating with the edge of the glass in the process of pressing the glass home into the rabbet, affords draft upon the curtain fabric, which extends past that shoulder along the face of the glass so as 50 to be gripped between the latter and the other shoulder, 4^b, of the rabbet,—to cause the curtain to extend taut on all sides of the window frame. But it is found desirable to provide for additional or what may be 55 termed final draft on the curtain at the final stage of clamping, and to effect the secure final grip of the frame members on the curtain fabric. For this purpose, at selected points in the contour of the window, 60 determined by experience with each particular shape of window,—that is, at points at which it is found that there is tendency for the curtain to be slack or to buckle, there are located the curtain engaging 65 means which comprise co-operating features

on the two frame members. These features are on one frame member at each of said engagements, a pair of longitudinally-extending ribs, 10, 10, and intermediate them, two longitudinally-spaced, preferably pointed, dowels, 11, 11, or sockets 12, 12 and at opposed position on the other frame member, two longitudinally-spaced dowel sockets, 12, 12, for receiving the dowels, 11, 11, or dowels, 11, 11, for entering the sockets 75 12, 12, and preferably a longitudinally extending rib, 13, aligned with the socket or dowel as the case may be and so extending from socket to socket, or dowel to dowel—except as interrupted by the hole, 5^a, for the screw, 5, as hereinafter mentioned,—and for a short distance beyond the two sockets or dowels at the remote sides. The two alternative equivalent constructions as to relative placing of dowels and 80 sockets with respect to the longitudinal ribs and interspaces as described, are seen respectively, on the side and end of the frame as represented in Figures 5 and 6, the sockets between the ribs being shown on 85 the end, and the dowels between the ribs being shown on the side. It is a matter of indifference which arrangement is employed at either place. It will be understood that the tapered or pointed dowels penetrate 90 the curtain fabric in the process of clamping the frame to the curtain, and that by their taper fitting the correspondingly tapered socket, they operate for draft upon the curtain for the purposes as above indicated; but also, by reason of their puncturing the fabric they tend to weaken it at 95 this point, thereby tending to cause a liability of the curtain to be pulled out by reason of rupture. To prevent this effect, 100 and at the same time to conserve the draft value of the tapered dowels is the purpose of the pair of longitudinally extending ribs which flank the dowel pins at both sides and engage the curtain fabric at considerably 105 extended lines past the punctures caused by the pointed dowels in order to take the stress off the fabric at those lines and prevent said stress from operating with 110 a tendency to rupture the fabric at the 115 points of puncture.

To relieve the fabric wall of strain from the weight of the glass, 2, and its surrounding frame, it is desirable to provide stay straps or supplemental supports for the 120 frame, indicated at 17 and 18, which are preferably located as seen in Figure 1, extending from some rigid element of the carriage and up over the top frame and back of the automobile body, as indicated, down 125 inside the curtain in immediate contact with either the surface of the curtain so as to be engaged with the curtain fabric between the opposed curtain-engaging areas of the two frame members, 3 and 4. For effecting a 130

very positive securement of these straps to the frame which they are to support and preventing them from interfering with or lessening the gripping engagement of the 5 frame members on the curtain fabric itself, the said curtain-engaging face of the frame member, at the side at which the stay strips are placed, which as illustrated is the inner member, 4, is slightly recessed as seen at 10 15, at the points at which the ends of the supporting strap are to be engaged with the frame as seen at 20 in Figure 4, and in these recesses there are provided the supplemental draft means above described, comprising the longitudinally extending ribs, 10, and the longitudinally spaced dowels, 11, the opposite side having, of course the sockets, 12, for the dowel pins. It will be seen that formation of the recesses, 15, be- 20 cause they are fully occupied with the stay straps in no way interferes with the operation of the curtain engaging features described for their primary purpose of engaging and exercising draft upon the curtain fabric.

I claim:—

1. In a carriage curtain window in combination with a glass, a two-membered frame whose two members engage the glass 30 between their opposed margins, one of said frame members having in the glass-engaging margin a groove with flaring sides, and an elastically-compressible gasket whose transverse section is of curvilinear outline, 35 lodged in said groove; the flaring walls of the groove being tangent to the curvilinear surface of the gasket when so lodged, and

the glass being tangent to the curved surface of the gasket opposite the angle between the flaring sides of the groove, and 40 means for securing the two frame members together with the gasket compressed between them against the glass and the flaring sides of the groove.

2. In the construction defined in claim 1 45 foregoing, the groove being approximately parabolic in cross section whereby the cross-sectional curvilinear gasket under compression occupies the bottom of the groove conforming to the cross-sectional curve 50 thereof.

3. In a carriage curtain window, in combination with a glass, a two-membered frame whose two members engage the glass 55 between their opposed inner margins, and the curtain fabric between the remainder of their opposed areas, said members having at intervals in their curtain-engaging areas, curtain draft and engagement means, each comprising in one member a pair of longitudinally-extending laterally-spaced ribs, and in their inter-space a plurality of longitudinally-spaced members of a dowel and 60 socket connection, and on the other member longitudinally-spaced sockets co-operating members of such connection, and proximate longitudinally to said engagement means, means for forcing and securing the two frame members together.

In testimony whereof, I have hereunto set 70 my hand at Chicago, Illinois, this 17th day of May, 1921.

LAWRENCE C. NELSON.
